UNITED STATES PATENT OFFICE.

GEORGE M. VOLTZ, OF ST. JOSEPH, MISSOURI, ASSIGNOR, BY DIRECT AND MESNE ASSIGNMENTS, TO CHARLES H. SCHULTZ, OF SAME PLACE.

VAPOR-BURNER.

SPECIFICATION forming part of Letters Patent No. 363,863, dated May 31, 1887.

Application filed September 2, 1886. Serial No. 212,511. (No model.)

To all whom it may concern:

Be it known that I, GEORGE M. VOLTZ, a citizen of the United States, residing at St. Joseph, in the county of Buchanan and State of Missouri, have invented a new and useful Improvement in Vapor-Burners, of which the following is a specification.

My invention relates to vapor-burners; and it consists in the peculiar construction and combination of devices, that will be more fully hereinafter set forth, and particularly pointed out in the claims.

In the drawings, Figure 1 is a side elevation of a vapor-burner embodying my improvement. Fig. 2 is a vertical sectional view of the same.

A represents a vapor-burner which may be either of the construction herein shown or of any other suitable form, and is provided with a depending arm, B, having near its upper end a horizontal hollow arm, C, the bore of which communicates with the inlet-pipe D. In the upper part of the arm C is formed a jet-orifice having a seat, E, for the reduced upper end of the vertically-movable needle-valve F. A sleeve, G, depends from the lower side of the arm C, and to the said sleeve is clamped the usual drip-cup, H.

I represents a horizontal bracket-arm, which is secured to the lower end of the depending arm B by means of a screw, K. A vertical opening is made in the outer end of the said bracket-arm, and the said opening is directly in line with the bore of the sleeve G.

The needle-valve is formed of two sections, f f', which are connected by a screw-coupling, f', which is interiorly screw-threaded, and is provided with a seat, f", at the upper end for the lower end of the upper valve section. The lower section of the valve is rigidly secured in the vertical opening of the bracket-arm I by means of a set-screw, L, and the upper section of the needle-valve extends up through the hollow sleeve, as shown.

From the foregoing description it will be readily understood that by partly turning the coupling of the needle-valve in one direction the said needle-valve will be lengthened, so as to cause the needle-point to rise in the minute opening in the valve-seat, and thus close the same and cut off the supply of fluid from the

burner. By turning the coupling in the contrary direction the needle-valve will be shortened, thereby lowering the upper section with the needle-point, thus causing the latter to be withdrawn from the opening in the valve seat. In order to turn the said coupling, I provide it with a handle, M, which is clamped firmly thereto by a set-screw, N.

The lower end of the sleeve G, through which the upper section of the needle-valve extends, is screw-threaded, and is provided with a packing-box, O, whereby leakage of the fluid or oil is prevented.

It will be noted that that portion of the needle-valve which extends through the sleeve is plain, and is not provided with screw-threads. This permits an exceedingly tight joint to be formed between the upper section of the needle-valve and the sleeve through which it passes, which is not subject to wear, and thus the danger of the burner leaking is obviated.

Heretofore, so far as I am aware, the needle-valves of vapor-burners have been provided with screw-threads and work in interiorly-threaded sleeves. This construction is objectionable, for the reason that the said valves frequently become clogged by the condensation of the fluid, thus rendering it extremely difficult to turn the valve, and is also objectionable for the reason that the screw-joint thus formed is very likely to leak, thus frequently causing disastrous consequences. These objections are overcome by the construction hereinbefore shown and described.

If it be desired to remove the needle-valve for any purpose, the screws K and L are loosened, thereby permitting the lower section of the needle-valve to be withdrawn from the bracket-arm, and the latter is then swung to one side, out of the way, and the upper section of the needle-valve may then be easily withdrawn from the sleeve.

I do not desire to limit myself to the precise construction hereinbefore described, as it is evident that modifications may be made therein without departing from the spirit of my invention.

Having thus described my invention, I claim—

1. In a vapor-burner, the combination of

the sleeve G, having the orifice E, the needle-valve section F, fitting in the sleeve and movable longitudinally therein, the rigid screw-threaded section f' , below the section F, and 5 the turning coupling-sleeve f'' , interiorly threaded and screwed to the section f' , and having the seat for the lower end of the section F, substantially as described.

2. The combination, with a vapor-burner, 10 of the rigid needle-valve section f' , provided with screw-threads, the valve-section f , having the point, and the coupling f'' , having the interior threads engaging the threaded section f' , and provided with the seat for the lower end 15 of valve-section f , substantially as described.

3. In a vapor-burner, the combination of

the sleeve G, having the orifice E, the needle-valve section F, movable longitudinally in the sleeve and having the point, the rigid screw-threaded section f' , arranged in line with and 20 below the section F, the screw-coupling sleeve interiorly threaded and connecting the opposing ends of the valve sections, and the lever or handle M, attached to the coupling-sleeve, to turn the latter, substantially as described. 25

In testimony that I claim the foregoing as my own I have hereto affixed my signature in presence of two witnesses.

GEORGE M. VOLTZ.
